(57) CLAIM

The ornamental design for yoga pants, as shown and described.

DESCRIPTION

FIG. 1 is a front, right and top perspective view of yoga pants, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top plan view thereof;

FIG. 8 is an enlarged bottom plan view thereof; and,

FIG. 9 is an enlarged view of portion 9 in FIG. 1 thereof. The dot-dash broken lines in the figures are included to identify areas of enlargement and form no part of the claimed design.

The broken lines shown in the drawings illustrate portions of the yoga pants that form no part of the claimed design.
